UNITED STATES PATENT OFFICE.

TOLBERT FANNING JASPER, OF DENTON, TEXAS.

DESIGN FOR A FENCE-POST.

No. 38,335.

Specification for Design.

Patented Dec. 4, 1906.

Application filed October 15, 1906. Serial No. 339,119. Term of patent 3½ years.

To all whom it may concern:

Be it known that I, TOLBERT FANNING JASPER, a citizen of the United States, residing at Denton, in the county of Denton and State of Texas, have invented a new, original, and ornamental Design for Fence-Post, of which the following is a specification, reference being had to the accompanying drawing, forming a part thereof.

The figure is a perspective view of a fence-post, showing my new design.

I claim—

The ornamental design for fence-post, as shown.

TOLBERT FANNING JASPER.
